COMBINED TELEPHONE STAND AND CABINET

Richard W. Swigert, Baltimore, Md.

Application April 8, 1953, Serial No. 24,417

Term of patent 7 years

(Cl. D26—14)

To all whom it may concern:

Be it known that I, Richard W. Swigert, a citizen of the United States of America, residing at Baltimore city, State of Maryland, have invented a new, original, and ornamental Design for a Combined Telephone Stand and Cabinet, of which the following is a specification, reference being had to the accompanying drawing, forming a part hereof.

Figure 1 is a perspective view of the combined telephone stand and cabinet showing my new design;

Figure 2 is a view showing the plain end of the stand and cabinet shown in Figure 1; and

Figure 3 is a view of the opposite end showing the ash tray and drawers.

The dominant features of my design reside in those portions shown in full lines.

I claim:

The ornamental design for a combined telephone stand and cabinet, as shown and described.

RICHARD W. SWIGERT.
